UNITED STATES PATENT OFFICE.

CHARLES LEWIS WEIL, OF PORT HURON, MICHIGAN; ELLA S. WEIL, ADMINISTRATRIX OF SAID CHARLES LEWIS WEIL, DECEASED.

STEAM SYSTEM FOR MANUFACTURING SALT AND THE LIKE.

1,391,811.

Specification of Letters Patent. Patented Sept. 27, 1921.

Application filed November 23, 1918. Serial No. 263,895.

To all whom it may concern:

Be it known that I, CHARLES L. WEIL, a citizen of the United States, and resident of Port Huron, in the county of St. Clair and 5 State of Michigan, have invented new and useful Improvements in Steam Systems for Manufacturing Salt and the like, of which the following is a specification.

This invention relates to a steam or vapor 10 system and more particularly to a steam system for manufacturing salt and the like, the present invention being applicable, *e. g.*, to salt making systems of the character disclosed in my former Patents No. 1,261,331 15 and No. 1,273,208.

In the manufacture of certain products it 20 is desirable, for commercial reasons, to vary the output. For example, the demand for salts of various grades varies throughout the year, thus making it necessary for the manufacturer either to maintain a constant output and store the excess output during the dull seasons, to be sold during the active season, or to vary the output in accord with 25 the varying demand. The first method is costly for the reason that it requires large warehouses and rehandling the product, but heretofore it has usually been resorted to for the reason that the known systems are not 30 adapted to be varied in output economically.

One object of the present invention is to provide a method and apparatus for manufacturing salt and the like, which will permit an economic variation of the output 35 without imposing an undue first-cost of installation and without entailing much time or labor in adjusting to different outputs and without rendering it necessary to leave much if any apparatus idle during periods 40 of reduced output. Another object of the invention is to provide a method and apparatus for re-utilizing the exhaust steam or vapor in evaporation systems such as salt-making systems, distillation systems, and 45 other steam systems, such as a power plant comprising a prime mover. Still another object is to avoid a decrease in efficiency as the output is decreased and indeed to attain an increasing efficiency as the output decreases.

Heretofore, in making salt and the like in closed evaporators, it has been common to employ a series of evaporators and connect the evaporators in series so that the vapor

or steam exhausted from one evaporator is 55 fed to the next evaporator, the exhaust steam from the second evaporator being conducted to the third evaporator, and so on to a condenser. In such systems the output may be regulated to a certain degree but the initial 60 cost and the subsequent maintenance of a system employing a series of evaporators is excessive, and there is no way of controlling 65 the economy of the systems throughout variations in output except possibly by means of complicated arrangements of pipes and valves. By the present invention a plurality 70 of evaporative effects may be obtained with a single evaporator, and the economy of the system may be controlled throughout vary- 75 ing output.

In one aspect the present invention involves a method of controlling the evaporative effect in the evaporator which comprises raising the pressure of a portion of 75 the steam exhausted from the evaporator, returning said steam to the evaporator at the raised pressure and regulating the exhaust steam returned to the evaporator so as to control the amount of exhaust heat re- 80 turned to the evaporator. The exhaust steam may be regulated either in quantity or in quality or both, as by varying the amount of exhaust steam returned to the 85 evaporator, or varying the pressure or de- 90 gree of superheat, or both. In order to compensate for heat losses in the system it is of course necessary to supply energy to the system. Such energy is preferably supplied 95 in the form of live steam and the live steam is employed to raise the pressure of the exhaust steam, preferably by ejecting the live steam into the exhaust steam and thus producing a mixed steam at a pressure intermediate the pressure of the live steam and 95 exhaust steam.

In another aspect the invention involves means for performing the aforesaid method. A cardinal feature of said means comprises a steam duct connecting the steam outlet of the evaporator with the steam inlet so that the exhaust steam issuing from the evaporator may be returned thereto, together with means for raising the pressure of the exhaust steam in transit from 105 the outlet to the inlet. My preferred means for raising the pressure of the exhaust steam comprises one or more steam

- ejectors deriving live steam from a suitable source. When employing a plurality of ejectors a series of steam loops is preferably interposed between the source of live steam and the evaporator with an ejector in each loop, the ejector in the first loop being connected to the source of live steam, the last loop being connected at its opposite ends to the inlet and outlet respectively of the evaporator, and each intermediate loop being connected at one end to the ejector in the next succeeding loop and at its other end to the next succeeding loop at a point in advance of the ejector therein.
- 15 In one embodiment of my improved system, a series of chambers are interposed between the source of live steam and the evaporator with a plurality of steam ducts connecting the source, chambers and evaporator together so that live steam is conducted through the chambers successively in one direction and exhaust steam is conducted successively through the chambers in the other direction, the steam ducts including a duct for feeding steam from one of the chambers to the evaporator, and a plurality of ejectors are arranged respectively to eject steam from each chamber into the steam entering the next chamber of lower pressure so as to raise the pressure in the next chamber of lower pressure... When employing such chamber together with a series of loops as above described the chambers are connected between successive loops and serve to connect the loops together. The chambers may comprise either elements distinct from the loops or portions of the steam ducts constituting the loops.
- Various adaptations and modifications of my invention will be evident from the following detailed description of certain specific embodiments of the invention and from the accompanying drawings, in which—
- Figure 1 is a diagram illustrating one application of the invention;
- Figs. 2, 3 and 4 comprise a set of diagrams illustrating one form of my new method; and
- Figs. 5, 6 and 7 comprise a set of diagrams illustrating another form of my improved method.
- The particular embodiment of the invention illustrated in Fig. 1, comprises a plurality of sets of apparatus which may be employed singly, or in series as shown in the figure. The set of apparatus at the right-hand side of the figure comprises a steam-operated device D in the form of an evaporator, a source of steam S, and a series of chambers C₁, C₂ and C₃ intermediate the source of steam S and the evaporator D. The source of steam S, evaporator D and chambers C₁, C₂ and C₃ are connected together by a series of steam ducts 1, 2, 3, 4, 5, 6 and 7. In the ducts 3, 5 and 7 are steam
- ejectors E₁, E₂ and E₃, respectively, connected to the steam ducts 1, 2 and 4. The source of steam S may comprise a steam boiler or any other source of steam. The evaporator D employed for the purpose of illustration is of the ordinary type comprising upper and lower liquid spaces 8 and 9 connected together by a plurality of pipes 10, the space in the central portion of the evaporator surrounding the pipes 10 constituting a heating chamber to which steam is supplied for the purpose of heating the contents of the evaporator. After the steam supplied to said heating chamber has given up a part of its heat it is exhausted through duct c to the atmosphere or to a condenser. The liquid level 11 preferably stands intermediate the top and bottom of the upper compartment 8. An exhaust duct 12 leads from the steam chamber C₁ and this duct may lead either to a condenser, a prime mover, another evaporator system, or to any other steam system, to be re-utilized.
- Assuming that the source S supplies steam at a pressure P₅ and that vapor is produced in the evaporator at the pressure P₁, the operation of the system above described is as follows:—The steam passes off from the evaporator D through duct 7 at pressure P₁ and is raised to a pressure P₂ in chamber C₃ by ejector E₃ deriving steam from duct 4 at a pressure P₃ produced in a manner which will presently be described. Part of the steam in chamber C₃ is returned to the evaporator through duct 6 at the pressure P₂ and part of the steam in chamber C₃ is fed to chamber C₂ through duct 5. The steam passing through duct 5 is raised to a pressure P₃ in chamber C₂ by means of ejector E₂ deriving steam through duct 2 at pressure P₄ from chamber C₁. Part of the steam fed into chamber C₂ at pressure P₃ is fed through duct 4 to ejector E₃ as described and the rest of the steam is fed through duct 3 to the chamber P₄. The steam entering chamber C₁ through duct 3 is raised to a pressure P₄ by ejector E₁ deriving steam from the source S through duct 1. Part of the steam supplied to chamber P₄ at pressure C₁ is fed through duct 2 to ejector E₂ as described and the remaining steam is exhausted from chamber C₁ through duct 12. The ejectors E₁, E₂ and E₃ are preferably adjusted to produce pressures in chambers C₁, C₂ and C₃ which form a geometrical progression with the pressures in the evaporator D and source S. Thus if the source S supplies steam at a pressure of 32 pounds and the evaporator produces a vapor at 2 pounds the pressures P₂, P₃ and P₄ in the chambers would be of the order of 4, 8 and 16 pounds respectively (all pressures herein referred to being absolute pressures).
- The operation of the system above de-

130

scribed may be made clearer by considering a concrete example of certain proportion of steam fed through the respective chambers and ducts, it being understood that the following is merely one concrete example, and that other proportions may be employed by suitably regulating the ejectors, by throttling the ducts, by exhausting steam from either the chamber C_2 or chamber C_3 instead of from the chamber C_1 , or in other ways, as will be apparent from subsequent descriptions herein.

One pound of steam passing from evaporator D through duct 7 at pressure P_1 may be raised to pressure P_2 in chamber C_3 by means of one pound of steam issuing from ejector E_3 at pressure P_3 . The two pounds of steam thus supplied to chamber C_3 at pressure P_2 may be equally divided between the ducts 5 and 6, one pound passing to the evaporator D to be re-utilized in heating the contents of the evaporator and the other pound passing to chamber C_2 . The pound passing to chamber C_2 may be raised to pressure P_3 by one pound of steam issuing from ejector E_2 at pressure P_4 . The two pounds of steam thus supplied to chamber C_2 at pressure P_3 may be equally divided between the ducts 3 and 4, one pound passing to ejector E_3 to raise a pound issuing from evaporator D at pressure P_1 to pressure P_2 , as described, and the other pound passing to chamber C_1 . The pound of steam passing through duct 3 may be raised to pressure P_4 in chamber C_1 by one pound of steam issuing from ejector E_1 at pressure P_5 . The two pounds of steam in chamber C_1 may be equally divided between the ducts 2 and 12, one pound passing to ejector E_2 to raise a pound of steam passing through duct 5 from pressure P_2 to pressure P_3 as described, and the other pound being exhausted through duct 12 either to a condenser, to another system similar to the one described, or to any other device adapted to utilize steam at pressure P_4 . Thus the system would operate continuously to maintain substantially constant pressures in the various chambers and to supply steam to the evaporator at pressure P_2 .

From the foregoing it will be evident that the ducts 1 to 7 are arranged in the form of loops, the ducts 2 and 3 constituting one loop, ducts 4 and 5 constituting a second loop, and the ducts 6 and 7 constituting a third loop. It will also be obvious that a part of the exhaust steam issuing from evaporator D passes successively through the chambers C_3 , C_2 and C_1 to the exhaust duct 12 and that a part of the live steam from source S passes successively through chambers C_1 , C_2 and C_3 to the evaporator D . The steam passing to the evaporator through duct 6 is a mixture of live steam and exhaust steam and by regulating the proportions of

live steam and exhaust steam the rate of heat supplied to the evaporator may be varied. It will be apparent from the foregoing and from subsequent descriptions that the number of chambers C_1 , etc., may be varied to suit different conditions as, for example, different pressures of live steam available, different pressures of exhaust vapor given off by the evaporator, different desired rates of evaporation, etc.

The tendency to superheat the steam in the respective chambers is counteracted by the evaporation of the moisture contained in the vapor from the evaporator. This tendency to superheat may be counteracted or regulated by varying the proportion of live steam to exhaust steam, by introducing moisture into the respective chambers, or in any other suitable manner. In starting up the system the desired conditions of steam pressure and steam flow may be established in any suitable manner, as by varying the effective size of the ejector openings, throttling the steam ducts, introducing live steam into the respective chambers at the desired pressure, as will be obvious to persons skilled in the art. It will also be understood that when working below atmospheric pressure the exhaust from the series of chambers would be connected to a condenser, that the air pump of the condenser could be connected directly to each of the various chambers, and that the respective chambers could be provided with such adjuncts as pressure gages, etc.

As illustrated in Fig. 1 the system above described may be employed in multiplex form by passing the exhaust steam from one set of apparatus to a second set and if desired from the second set to still other sets. Thus in Fig. 1 the duct 12 is connected to the first of a series of steam chambers C_4 , C_5 and C_6 associated with a second evaporator D_1 , the chambers being connected together and to the evaporator by means of ducts 13, 14, 15, 16 and 17 in a manner similar to the connections in the right-hand set, with ejectors E_4 and E_5 in ducts 15 and 17 respectively. The pressures in the second set of chambers may be regulated as desired but they preferably correspond to the pressures in the first set of chambers, the pressures in chambers C_4 , C_5 and C_6 being P_4 , P_3 and P_2 respectively. An exhaust duct 18 leads off from chamber C_5 and this duct may be connected to the first of a third set of chambers C_7 and C_8 . The chamber C_8 is connected to the inlet 19 and outlet 20 of evaporator D_2 by ducts 21 and 22, and the chamber C_7 is connected to an ejector E_6 in duct 22 through duct 23, the exhaust duct 24 leading off from chamber C_8 . While the pressures in chambers C_8 and C_7 may be regulated as desired they preferably correspond to the pressures in the corresponding

110

115

120

125

130

chambers of the other sets, with a pressure of P_3 in chamber C_7 and a pressure of P_2 in chamber C_8 . The steam exhausted through duct 24 is preferably conducted to a condenser. When employing a plurality of sets of apparatus as shown in Fig. 1 the evaporative effect of the system may be varied by disconnecting one or more sets of apparatus. Thus a single effect may be obtained by employing only the right-hand set of apparatus, a double effect may be obtained by employing the right-hand set and the middle set, and a triple effect may be obtained by employing all three sets. It will be understood that by employing a suitable number of steam chambers in the respective sets any desired number of sets may be employed.

However, in accordance with the objects of the present invention I prefer to vary the output in a different manner from that above described in connection with Fig. 1 and in a manner such that only a single set of apparatus is required to obtain either a single, double, triple, etc., effect. One such method may be performed as illustrated in Figs. 2, 3 and 4, with apparatus similar to the set of apparatus shown at the right-hand end of Fig. 1, comprising a source of live steam S , an evaporator D , ejectors E_1 , E_2 and E_3 , chambers C_1 , C_2 and C_3 , and steam ducts 1, 2, 3, 4, 5, 6 and 7 connecting the respective chambers together and to the source S and evaporator D . With this single system different evaporative effects may be obtained in the following manner:

To obtain a single effect the system may be adjusted to operate as described in connection with the right-hand set of apparatus in Fig. 1 whereby one pound of steam at pressure P_3 will raise one pound of steam at pressure P_1 to pressure P_2 in chamber C_3 , one pound of steam at pressure P_1 will raise one pound of steam at pressure P_2 to pressure P_3 in chamber C_2 , and one pound of steam at pressure P_3 will raise one pound of steam at pressure P_3 to pressure P_4 in chamber C_1 . Thus the system will continuously supply steam to the evaporator at the rate of one pound at pressure P_2 per unit of time, during which unit of time one pound of live steam is supplied to the system at pressure P_5 and one pound of steam is exhausted from chamber C_1 at pressure P_4 through duct 12 (Fig. 2), 12' (Fig. 3) and 55 12'' (Fig. 4).

In order to obtain a double evaporative effect with the single system, steam is exhausted from chamber C_2 instead of chamber C_1 , as illustrated at 12' in Fig. 3, and the 60 ejectors are regulated so that different proportions of live steam and exhaust steam are mixed together in the respective chambers. For example, two pounds of steam issuing from evaporator D at pressure P_1 65 may be raised to pressure P_2 in chamber C_3

by two pounds of steam issuing from ejector E_3 at pressure P_3 . Two of these four pounds of steam are returned to the evaporator through duct 6, while two pounds are fed to chamber C_2 through duct 5. The two pounds of steam passing through duct 5 may be raised from pressure P_2 to pressure P_3 in chamber C_2 by two pounds of steam issuing from ejector E_2 at a pressure P_4 . Of the four pounds of steam introduced into chamber C_2 per unit of time, two pounds are fed to ejector E_3 through duct 4 as described, one pound is fed through duct 3 to chamber C_1 and one pound is exhausted through duct 12'. The pound of steam fed to chamber C_1 through duct 3 is raised from pressure P_3 to pressure P_4 by one pound of steam from the source S at pressure P_5 . Thus during a single unit of time while one pound of live steam at pressure P_5 is supplied to the system as in Fig. 2, two pounds of steam, instead of one pound as in Fig. 2, are fed to the evaporator at pressure P_2 , and one pound of steam is exhausted at pressure P_3 , instead of pressure P_4 as in Fig. 2. Thus during the same unit of time twice as much heat is supplied to the evaporator as described in connection with Fig. 2, whereby a double evaporative effect is produced.

To obtain a triple evaporative effect steam is exhausted from chamber C_3 , as illustrated in Fig. 4 at 12'', and the ejectors are regulated to produce the following proportions of live steam and exhaust steam in the respective chambers. Three pounds of steam issuing from evaporator D at pressure P_1 are raised to pressure P_2 in chamber C_3 by three pounds of steam issuing from ejector E_3 at pressure P_3 . Of the six pounds of steam thus supplied to chamber C_3 at pressure P_2 , three pounds are returned to the evaporator through duct 6, two pounds are fed to the chamber C_2 through duct 5 and one pound is exhausted through duct 12''. The two pounds of steam passing through duct 5 are raised to pressure P_3 in chamber C_2 by two pounds of steam issuing from ejector E_2 at pressure P_4 . Of the four pounds of steam thus supplied to chamber C_2 , three pounds are fed to ejector E_3 as described and one pound is fed to chamber C_1 through duct 3. The steam passing through duct 3 is raised from pressure P_3 to pressure P_4 by one pound of steam issuing from ejector E_1 at pressure P_5 . The two pounds of steam fed to chamber C_1 at pressure P_4 are fed to ejector E_2 as described. Thus, during a single unit of time while one pound of steam is being supplied to the system at pressure P_5 , as in Figs. 2 and 3, three pounds of steam are being supplied to the evaporator at pressure P_2 , instead of two pounds as in Fig. 3 and one pound as in Fig. 1. One pound of steam is exhausted

in Fig. 4 during the unit of time as in Figs. 2 and 3, but from chamber C_3 instead of chamber C_2 in Fig. 3 and chamber C_1 in Fig. 2. Obviously by employing a larger number of steam chambers a greater number of evaporative effects may be obtained; also, that effects intermediate the single, double, triple, etc., effects may be obtained by employing a greater number of steam chambers 10 or by regulating the ejectors differently.

Another embodiment of my improved method of regulating the evaporative effects in a single evaporator is illustrated in Figs. 5, 6 and 7. According to this method, a single evaporative effect may be obtained by employing a single steam chamber intermediate the source of live steam and the evaporator as illustrated at C_3 in Fig. 5, the chamber C_3 being connected to the evaporator D through the ducts 6 and 7 as in Figs. 2 to 4. Instead of supplying live steam to chamber C_3 through the medium of chambers C_1 and C_2 and associated ducts as in Figs. 2 to 4, live steam is supplied directly 20 from the source S to the ejector E_3 . Steam is exhausted from chambers C_3 through duct 25. The chambers C_1 and C_2 , ejectors E_1 and E_2 and associated ducts which are not used in obtaining a single effect are shown 30 in dotted lines in Fig. 5, it being understood that to obtain double and triple effects as hereinafter described these chambers will be provided, but will be cut off from the connections shown in full lines in Fig. 5 in obtaining the single effect.

The operation of the system shown in Fig. 5 is as follows: One pound of steam exhausted from evaporator D through duct 7 is raised to pressure P_2 in chamber C_3 by one 40 pound of steam issuing from ejector E_3 at pressure P_s . Of the two pounds of steam thus delivered to chamber C_3 , one pound is returned to the evaporator through duct 6 and one pound is exhausted through duct 25.

To obtain a double effect according to the last mentioned method, two steam chambers C_2 and C_3 may be connected in series as illustrated in full lines in Fig. 6, the chamber C_3 being connected to the evaporator by ducts 50 6 and 7 as before and the chamber C_2 being connected to the chamber C_3 by ducts 4 and 5. The ejector E_3 is supplied with steam through duct 4 and the ejector E_2 in duct 5 is supplied with steam through duct 27 directly 55 from the source S. The chamber C_1 , ejector E_1 , and associated ducts are cut off from the system as indicated by dotted lines.

The operation of the system shown in Fig. 6 is as follows: Two pounds of steam issuing from the evaporator at pressure P_1 are raised to pressure P_3 by two pounds of steam issuing from ejector E_3 at pressure P_s . Of the four pounds of steam thus delivered to chamber C_3 , two pounds are returned to 65 the evaporator through duct 6, one pound

is delivered to chamber C_2 through duct 5, and one pound is exhausted through duct 25. The pound of steam passing through duct 5 is raised from pressure P_3 to pressure P_6 by one pound of steam issuing from ejector 70

E_2 at pressure P_s . The two pounds of steam thus delivered to chamber C_2 are both conducted through duct 4 to the ejector E_3 as described. The pressure and rate of flow of the steam in the various chambers may be 75 controlled by regulating the ejectors or by throttling the ducts as above described in connection with the preceding methods.

In order to obtain a triple evaporative effect according to the last mentioned method, 80 all of these chambers C_1 , C_2 and C_3 are connected in series as illustrated in Fig. 7, the connections in this figure being identical with the connections in Fig. 4 where a triple effect may be obtained as above described. 85 The triple effect obtained according to the last mentioned method by the connection shown in Fig. 7 is preferably obtained in the same manner as hereinbefore described in connection with Fig. 4.

The pressures P_1 , P_2 and P_s in Figs. 5 to 7 preferably increase in the order indicated by the subscripts so that the pressure P_4 in the last chamber in Fig. 5 is greater than the pressure P_3 in the corresponding chamber in Fig. 6, and the pressure P_5 in Fig. 6 is preferably greater than the corresponding pressure P_2 in Fig. 7. Thus while one pound of steam at pressure P_s is supplied to the system during one unit of time in each 90 figure, one pound of steam is being delivered to the evaporator at pressure P_1 in Fig. 5, two pounds of steam are being delivered to evaporator D at pressure P_3 in Fig. 6, and three pounds of steam are being delivered 95 to evaporator D at pressure P_2 in Fig. 7. By choosing suitable pressures in the various chambers, the rate of evaporation may be varied to any extent by the method illustrated in Figs. 5 to 7. If the pressures P_1 , 100 P_4 and P_s in Fig. 5 were 2, 8, and 32 pounds respectively and if the pressures P_1 , P_3 , P_6 and P_s in Fig. 6 were 2, 5, $12\frac{1}{2}$ and 32 pounds respectively and if the pressures P_1 , P_2 , P_5 , P_7 and P_s in Fig. 7 were 2, 4, 8, 16 and 32 110 pounds respectively, the rate of evaporation per square foot of heating surface would be greater in Fig. 5 than in Fig. 6, and greater in Fig. 6 than in Fig. 7.

A comparison of the two specific embodiments of my improved method described in connection with Figs. 2 to 4 on the one hand and Figs. 5 to 7 on the other hand will indicate that in the former method the same number of steam chambers are employed in 120 obtaining the different evaporative effects while in the latter method a variable number of steam chambers are employed; that in the former method the same number of 125 ejectors are employed in obtaining the vari- 130

ous effects while in the latter method a variable number of ejectors are employed; that the steam is exhausted from different chambers according to the former method and 5 from the same chamber according to the latter method; that the pressure in the evaporator preferably remains constant in the first method, while it varies in pressure in the latter method; and that the ejectors 10 are preferably varied in size in both methods. However, it is to be understood, that the exhaust steam may be exhausted from different chambers in the latter method as in the former method; that the 15 pressure in the evaporator may be varied in the former method as in the latter method; that the pressure of the steam delivered to the evaporator may be maintained constant in the latter method as in the former 20 method; and that other variations may be made within the scope of the present invention as defined by the appended claims.

As hereinbefore stated the pressures in the steam chambers may be regulated as desired to meet different conditions of operation. However, the following considerations should be borne in mind in connection with the application of the invention to evaporator systems.

30 In controlling the evaporative effect by operating a battery of evaporators in series, with the first evaporator exhausting to the second evaporator and so on, as hereinbefore stated to be a common practice, and as commonly involving evaporating vessels of 35 large diameter and a limited temperature range, the range of temperature is divided between the respective evaporators of the battery. Thus, when employing two evaporators of a battery to obtain a double effect the temperature range is divided substantially by two, when employing three evaporators to obtain a triple effect the temperature range is divided substantially by three, 40 etc. Thus in order to obtain the desired output with a multiple or battery system the heating surface of each evaporator must be made disproportionately large to offset the limited temperature range available therein. 45 In varying the evaporative effect in a single evaporator according to the present invention the range of temperature is not divided between a series of evaporators and consequently a greater output is available with a 50 predetermined amount of heating surface or conversely less heating surface is required for a predetermined maximum output.

I have described the present invention with particular reference to a system for 55 manufacturing salt but it will be understood that the invention, in certain of its aspects, is applicable to systems for manufacturing sugar, soap, glycerin, etc., which employ evaporative processes; and that it is

applicable to steam power plants and other steam systems in which the exhaust steam is capable of being re-utilized. It will therefore be understood that the references in the specification and claims to the manufacture of salt are employed in an illustrative sense 65 and not in a definitive sense. The term "live steam" is employed herein to designate steam at a pressure higher than the pressure of the exhaust steam which is re-utilized and is therefore employed merely in 70 contradistinction to exhaust steam. The term "exhaust steam" is intended to cover either steam or vapor, and it is also intended to cover any kind of vapor whether water vapor or other vapor. I have herein referred to steam chambers as distinct elements but the chambers may if desired be constituted by portions of the steam ducts as illustrated in Fig. 7 where the horizontal portions of the ducts constitute the steam 75 chambers.

I claim:

1. In a system of the character described the combination of a steam-operated device having a steam inlet through which steam may be supplied thereto and having a steam outlet through which steam may be exhausted therefrom, a steam duct connecting said outlet with said inlet so that exhaust steam issuing from said outlet may be returned 90 through said inlet, a steam ejector in said duct for raising the pressure of the exhaust steam, a second steam duct connecting said ejector with said first duct at a point in advance of said ejector so that steam may be supplied from said first duct to said ejector after having been raised in pressure by said ejector, a second steam ejector in said second duct for raising the pressure of the steam in said second duct in 95 transit from said first duct to said first ejector, and means for supplying steam to said second ejector at a pressure higher than the pressure in said second duct in the rear of 100 said second ejector.

2. In a system of the character described the combination of a source of steam, a steam-operated device having a steam inlet through which steam may be supplied thereto and having a steam outlet through which steam may be exhausted therefrom, a series of steam loops interposed between said source and said device, the ejector in the first loop being connected to said source of steam, the last loop being connected at its opposite 115 ends to said inlet and said outlet, and each intermediate loop being connected at one end to the ejector in the next succeeding loop and at its other end to the next succeeding loop at a point in advance of the ejector 120 therein.

3. In a system of the character described for manufacturing salt and the like, the

combination of a source of live steam, an evaporator, a plurality of intermediate chambers, steam ducts connecting said source, evaporator and chambers together so 5 that exhaust steam is conducted through said chambers successively in one direction and live steam is conducted successively through said chambers in the other direction, and ejectors for ejecting the steam from each chamber 10 into the steam entering the next chamber of lower pressure so as to raise the pressure of the steam entering the next chamber of lower pressure, said ducts including a duct for feeding steam from one of said chambers 15 to said evaporator.

4. In a system of the character described the combination of a source of live steam, a steam-operated device having a steam inlet and a steam outlet, a series of steam chambers 20 intermediate said source and said device, a steam conduit leading from each chamber to the next preceding chamber, a steam conduit leading from said outlet to the last chamber, an ejector in each of said 25 conduits, a steam duct leading from said source to the ejector in the first of said conduits, a steam duct leading from each of said chambers except the last chamber to the ejector in the conduit leading to the next succeeding chamber, and a steam duct leading 30 from the last chamber to said inlet.

5. In the manufacture of salt and the like by evaporation in a closed evaporator, the method of effecting the evaporation comprising 35 supplying live steam in one direction through a series of steam loops to the evaporator, exhausting steam from the evaporator through said series of loops in the other direction, successively raising the pressure 40 of the exhaust steam in transit through said loops by means of said live steam, at the same time reducing the pressure of the live steam in transit to the evaporator, and conducting a portion of the exhaust steam back 45 to the evaporator after having been raised in pressure as aforesaid.

6. In the manufacture of salt and the like by evaporation in a closed evaporator, the method of effecting the evaporation comprising 50 supplying live steam in one direction through a series of steam loops to the evaporator, exhausting steam from the evaporator through said series of loops in the other direction, successively raising the pressure 55 of the exhaust steam in transit through said loops by means of said live steam, at the same time reducing the pressure of the live steam in transit to the evaporator, and regulating the exhaust steam returned to the 60 evaporator so as to control the amount of exhaust heat returned to the evaporator.

7. In the manufacture of salt and the like by evaporation in a closed evaporator, the method of effecting the evaporation comprising 65 supplying live steam in one direc-

tion through a series of steam loops to the evaporator, exhausting steam from the evaporator through said series of loops in the other direction, successively raising the pressure of the exhaust steam in transit through 70 said loops by means of said live steam, at the same time reducing the pressure of the live steam in transit to the evaporator, and regulating the amount of exhaust steam returned to the evaporator so as to control the 75 amount of exhaust heat returned to the evaporator.

8. In the manufacture of salt and the like by evaporation in a closed evaporator, the method of effecting the evaporation comprising 80 supplying live steam in one direction through a series of steam loops to the evaporator, exhausting steam from the evaporator through said series of loops in the other direction, successively raising the pressure 85 of the exhaust steam in transit through said loops by means of said live steam, at the same time reducing the pressure of the live steam in transit to the evaporator, and regulating the pressure of the exhaust steam returned to the evaporator so as to control 90 the amount of exhaust steam returned to the evaporator.

9. In the manufacture of salt and the like by evaporation in a closed evaporator, the method of effecting the evaporation comprising 95 supplying live steam in one direction through a series of steam loops to the evaporator, exhausting steam from the evaporator through said series of loops in the other direction, successively raising the pressure 100 of the exhaust steam in transit through said loops by means of said live steam, at the same time reducing the pressure of the live steam in transit to the evaporator, and regulating both the pressure and the amount 105 of the exhaust steam returned to the evaporator so as to control the amount of exhaust heat returned to the evaporator.

10. In manufacturing salt and the like by evaporation in a closed evaporator, where live steam is available at a relatively high pressure and exhaust steam is produced in the evaporator at a lower pressure, the method of controlling the evaporation comprising 110 passing the live steam and exhaust steam in opposite directions through a series of steam loops so as progressively to lower the pressure of the live steam in one direction and progressively to raise the pressure 115 of the exhaust steam in the other direction in a plurality of stages, and feeding steam to the evaporator from one of said stages at a pressure intermediate the pressures of the live steam and exhaust steam.

11. In manufacturing salt and the like by evaporation in a closed evaporator, where live steam is available at a relatively high pressure and exhaust steam is produced in the evaporator at a lower pressure, the 120 125

method of controlling the evaporation comprising passing the live steam and exhaust steam in opposite directions through a series of steam loops so as progressively to lower the pressure of the live steam in one direction and progressively to raise the pressure of the exhaust steam in the other direction in a plurality of stages, and regulating said intermediate stages so as to control the pressure of the steam fed to the evaporator.

12. In manufacturing salt and the like by evaporation in a closed evaporator, where live steam is available at a relatively high pressure and exhaust steam is produced in the evaporation comprising passing the live steam and exhaust steam in opposite directions through a series of steam loops so as progressively to lower the pressure of the live steam in one direction and progressively to raise the pressure of the exhaust steam in the other direction in a plurality of stages, and regulating both the number of said intermediate stages and the pressures in the stages so as to control the pressure of the steam fed to the evaporator.

20 to raise the pressure of the exhaust steam in the other direction in a plurality of stages, and regulating the number of said intermediate stages so as to control the pressure of the steam fed to the evaporator.

25 13. In manufacturing salt and the like by evaporation in a closed evaporator, where live steam is available at a relatively high pressure and exhaust steam is produced in the evaporator at a lower pressure, the method of controlling the evaporation comprising passing the live steam and exhaust steam in opposite directions through a series of steam loops so as progressively to lower the pressure of the live steam in one direction and progressively to raise the pressure of the exhaust steam in the other direction in a plurality of stages, and regulating the pressure in said intermediate stages so as

to control the pressure of the steam fed to the evaporator.

14. In manufacturing salt and the like by evaporation in a closed evaporator, where live steam is available at a relatively high pressure and exhaust steam is produced in the evaporator at a lower pressure, the method of controlling the evaporation comprising passing the live steam and exhaust steam in opposite directions through a series of steam loops so as progressively to lower the pressure of the live steam in one direction and progressively to raise the pressure of the exhaust steam in the other direction in a plurality of stages, and regulating both the number of said intermediate stages and the pressures in the stages so as to control the pressure of the steam fed to the evaporator.

15. In manufacturing salt and the like by evaporation in a closed evaporator, where live steam is available at a relatively high pressure and exhaust steam is produced in the evaporator at a lower pressure, the method of controlling the evaporation comprising passing the exhaust steam in one direction through a series of steam chambers, passing the live steam through the series of chambers in the other direction, progressively raising the pressure of the steam in the successive chambers in the first direction by ejecting steam from the next chamber of higher pressure thereinto, and feeding steam from one of said chambers to the evaporator.

Signed by me at Port Huron, Michigan, this thirteenth day of November, 1918.

CHARLES LEWIS WEIL.
